UNITED STATES PATENT OFFICE

GILBERT MURPHY, OF FRANKLIN, NEW HAMPSHIRE, ASSIGNOR TO ACME KNITTING MACHINE & NEEDLE COMPANY, OF FRANKLIN, NEW HAMPSHIRE, A CORPORATION OF NEW HAMPSHIRE

KNITTING MACHINE

Application filed April 28, 1919. Serial No. 293,113.

In knitting certain kinds of goods, especially stockings, it is desirable to rib a part of the article and to knit an adjacent part plain. This is particularly true in children's 5 stockings in which the leg usually is ribbed, while the foot and part of the ankle are knit plain. Also in men's and in certain grades of women's stockings a ribbed cuff is knitted at the top of the leg. Machines have been 10 proposed heretofore in which either plain work or ribbed work could be knit, as desired, and in which a change from one kind of knitting to another could be made, so that stockings of the types just described could 15 be knit in a single machine. These machines, however, have proved impractical, and consequently it is the universal practice at the present time to perform the ribbing and plain knitting operations in different machines. For instance, in knitting stockings 20 of the character above referred to, it is usually the practice to knit the ribbed top or cuff in one machine and then to transfer it to another machine which does the plain knitting. This obviously is inconvenient, is 25 wasteful of labor and requires the use of two types of machines.

The present invention has for its chief object to devise a thoroughly practical machine which will knit both plain and ribbed goods and in which the change from one style of knitting to another can be made on a given piece of work at will. It is a further object of the invention to devise a machine of this type in which the change from ribbed to plain work, or vice versa, can be made automatically so that the machine will knit goods requiring both plain and ribbed knitting and will change automatically from 30 one type of knitting to the other without requiring attention on the part of the attendant.

The invention will be herein described as embodied in a machine designed especially for knitting stockings, although it will be understood by those skilled in this art that the invention is not limited to this class of work.

The nature of the invention will be readily understood from the following descrip-

tion when read in connection with the accompanying drawings and the novel features will be particularly pointed out in the appended claim.

Referring now to the drawings,

Figure 1 is a vertical cross sectional view through the needle cylinder and adjacent parts of a machine embodying this invention;

Fig. 2 is a front elevation of the machine;

Fig. 3 is a left side elevation of the machine shown in Fig. 2, certain parts at the head of the machine being omitted;

Fig. 4 is a vertical cross sectional view through a part of the needle cylinder and needle dial showing the relationship of the two sets of needles;

Fig. 5 is a diagrammatic view illustrating the manner in which the ribbing operation is performed;

Fig. 6 is a plan view of a mechanism which is utilized to hold the central needle dial stationary;

Fig. 7 is a view similar to Fig. 6 showing the parts in a different position;

Fig. 8 is a plan view of the needle dial with which the machine is equipped, showing the ribbing needles mounted therein;

Fig. 9 is a horizontal cross sectional view taken substantially on the line 9—9, Fig. 1;

Fig. 10 shows a series of views illustrating different positions of the parts that control the operation of the ribbing needles;

Fig. 11 is a view of the lower face of the adjustable cam that controls the ribbing needles;

Fig. 12 is a vertical cross sectional view on the line 12—12, Fig. 11;

Figs. 13 and 14 are views similar to Fig. 11 showing the cam in different positions of adjustment;

Fig. 15 is a side elevation of the parts shown in Fig. 13;

Fig. 16 is a side view of a cam wheel used in the machine;

Fig. 17 is a cross sectional view on the line 17—17, Fig. 16, through one of the lugs on the cam wheel;

15 The drawings show the invention applied to the machine shown and described in the Hemphill Patent No. 629,503, granted July 25, 1899, and reference should be made to this patent for a detailed description of the construction and operation of the machine.

20 For the purposes of the present specification it may be stated that the machine shown in the accompanying drawings, so far as it departs from the construction of the Hemphill machine, consists in additions to the machine, all of the parts of the regular Hemphill machine being used and these parts operating in their usual manner. Briefly stated, these additions consist in a horizontal set of needles mounted on a dial plate and co-operating with the upright cylindrically arranged needles of the Hemphill machine to perform the ribbing operation. This horizontal set of needles is thrown out 25 of operation when the machine is knitting plain work and is brought into operation only when it is desired to knit ribbed work. Controlling mechanism is provided through which the horizontal or ribbing needles may be thrown into and out of operation, and the 30 machine is equipped with means controlled by the pattern chain for automatically throwing the ribbing needles into and out of operation at predetermined points in the cycle of operations of the machine. The machine shown is designed to knit a stocking having a ribbed leg or a ribbed top and plain leg and foot, and then to repeat this operation, knitting a continuous tubular fabric fashioned at the heel and toe, the relative 35 proportions of the ribbed and plain parts of the work being controlled by the pattern chain.

40 Referring now particularly to Figs. 1, 2, 3 and 9 of the drawings, the needles with which the Hemphill machine regularly is equipped are designated at 2, these needles being mounted in vertical guideways formed for them in a needle cylinder 3 that is supported in the upper end of a web guide 4. 45 Each of the needles 2 is provided with a heel 5 that rides on the upper edge of a cam 6 fast on the rotating cam plate 7. This cam plate 7 rotates in a cup-shaped bearing 8 provided in the frame of the machine and is 50 provided with bevelled teeth that engage the

teeth of a bevel gear 9 fast on the main shaft 10 of the machine, this bevel gear operating to rotate the entire cam plate and the parts supported thereon. The needles 2 project upwardly just inside a thread ring 12 which 70 rotates with the cam plate 7. The machine also is provided with a series of web holders or sinkers 13 mounted in radial grooves in a bed 14 which encircles the upper part of the needle cylinder 3. The needles 2 and sinkers 75 13 remain stationary while the cam plate 7, cam 6 and thread ring 12 revolve in unison, as is well understood by those skilled in this art.

80 The parts so far described are all constructed, arranged and operate as they do in the commercial Hemphill machine and for detailed information as to the construction and operation of these parts and of the supporting and operating mechanisms therefor, 85 reference should be made either to the Hemphill machine or to the Hemphill patent above designated.

85 The ribbing needles are indicated at 15. These needles are mounted in radial slots 90 15' formed in the upper horizontal surface of a dial plate 16, Figs. 1 and 8, which is secured to the lower end of a post 17. Each of the needles 15 is provided with a heel 18 that runs in a cam path or groove 19 formed 95 in a cam 20.

95 It is necessary to move these needles backward and forward both for the purpose of enabling them to perform the knitting operation and also for the purpose of bringing them into and out of operation, as desired, during the knitting of a stocking or other article of work. Both of these operations are performed by, or through, the cam 20. The backward and forward movements 100 of the needles necessary to enable them to perform their knitting operations, are produced by the rotation of the cam and the peculiar shape of the cam path, and the control of the needles is effected by making 105 certain parts of the cam adjustable so that the needles can be pushed out into the proper path to enable them to reach the thread and perform their knitting functions, or they can be drawn back to such a point that the thread cannot be placed in the hooks of the needles, and consequently they will be rendered inoperative so far as the knitting 110 operation is concerned.

115 In order to rotate the cam, it is mounted 120 on a head 21, Fig. 1, from which a sleeve 22 extends upwardly, encircling the post 17, and the upper end of this sleeve is secured in a clamp 23 formed on a yoke 24 which is bolted to the top of two brackets 25 and 26 secured at diametrically opposite points 125 on the revolving cam plate 7.

130 In order to hold the dial 16 stationary, the post 17 is extended up through the yoke 24 and is held against rotation by a sliding

latch mechanism. This mechanism is made necessary by the fact that the thread must be led from the cop, or other source of supply, (not shown) to the thread eye 27 in the revolving thread ring 12. A plate 28 is secured by a bolt 30 to the yoke 24 and has an eccentric slot 31 cut therein, as best shown in Figs. 6 and 7. This plate, therefore, revolves with the cam plate 7 and the thread ring 12. The thread from the source of supply is led through a thread tube 32 secured in the rotating plate 28, this tube being substantially in vertical alinement with the thread eye 27 in the thread ring 12. The rotating parts are steadied by a rigid bracket 33 fixed to the frame of the machine, the plate 28 revolving in a circular opening cut in this bracket, as clearly shown in Fig. 1. An annular plate 34, Figs. 6 and 7, is secured to the bracket 33 concentrically with the plate 28 and is provided with bosses 35 and 36 through which slide-ways are cut for a latch 37. This latch consists of a bar, rectangular in cross section, mounted to slide through an opening formed for it in a head 38 integral with the post 17 and also through a collar 40 that encircles said head. Another collar 41 bears on the collar 40 and is clamped on the post 17 by a nut 42 threaded on the reduced upper end of the post.

A roll 43 mounted on a stud projecting from the lower side of the slide 37 runs in the eccentric groove 31, and consequently, as the plate 28 revolves with the yoke 24 and cam 20, the slide or latch 37 will be moved backward and forward in the guideway formed through the parts 38, 40, 35 and 36. The thread tube 32 is located on the side of the eccentric plate 28 opposite to the point at which the groove 31 lies at its maximum distance from the center of rotation of the plate, and the slide 37 is made of such a length that when the thread tube 32 arrives at the path of movement of the slide, the eccentric groove 31 and roll 43 will have moved the slide or latch 37 away from the boss adjacent to the thread tube at that particular instant (as shown in Fig. 7) and thus avoid any interference between the slide and the thread tube. This construction thus holds the needle dial 16 stationary, while the cam 20 rotates, and also guides the thread to the thread eye 27 in the thread ring without any interference from stationary or non-rotating parts of the machine.

The construction of the cam 20 is best shown in Figs. 11 to 14, inclusive. Referring to these figures it will be seen that the cam comprises two members 44 and 45 which are secured to the plate 21 by dowel pins and screws. Co-operating with these parts are two members 46 and 47 similarly secured to the plate 21. These parts are

spaced from each other to form grooves *a* and *b* that constitute part of the cam path for controlling the ribbing needles 15. Another cam member 48 having a groove *c* therein, which substantially connects the ends of the grooves *a* and *b*, is pivoted on the plate 21 at 49 so that it can swing inward or outward with reference to the periphery of the head 21. A similar cam member 50 is pivoted to the plate or head 21 at 51 and is provided with a groove *d* connecting the opposite ends of the cam grooves *a* and *b*. In order to limit the range of movement of the cam members 48 and 50, and also for the purpose of moving them when desired, pins 52 and 53, respectively, are screwed into these cam members from their upper sides and extend through slots 54 and 55, respectively, in the head 21.

In knitting plain work the cam members 48 and 50 are moved inwardly to the inner limits of their range of movement as shown in Fig. 11. In this position the cam 20 holds the ribbing needles 15 out of their knitting or operative positions. Consequently, if the machine is operated at this time it will knit plain goods in exactly the manner that the Hemphill machine operates. When, however, the cam members 48 and 50 are manipulated in the proper manner, as will later be described, to set the cam member 48 or 50 which is at the front of the machine, that is, toward the thread opening 27 in the thread ring, in its outermost position, and the other cam member in its intermediate position, as shown in Fig. 14, the ribbing needles then will be brought into operation. That is, they will be moved in and out in the proper time relationship to the operation of the vertical needles to catch the thread and they will co-operate with the vertical needles to knit a ribbed piece of work.

The manner in which this knitting operation is performed will be readily understood from an inspection of Figs. 4, 5 and 8. Assuming for the moment that the horizontal needles 15 are held back in their inoperative positions, it will be understood from an inspection of Fig. 5 that the vertical needles perform the knitting operation by catching the thread *T* as they descend from their upper positions, in which they are shown at the right of Fig. 5, to their lower positions approximately at the middle of said figure, pulling loops of thread through the loops held on the shanks of the needles, then casting off the latter loops as the needles drop below the level of the sinker plates 13 and finally rising again to their normal positions as shown at the left of Fig. 5. This is the normal operation of the Hemphill machine. When, however, the ribbing needles 15 are thrown into operation, these needles are brought successively into an advanced posi-

tion in time to catch the thread as it is pulled downwardly by the vertical needles 2. In Fig. 5, 15^a shows one of the horizontal needles in the act of grasping a loop of thread which is pulled down into the hook of the needle 15^a by the vertical needles 2 on opposite sides of it. This needle 15^a is next pulled backwardly far enough to cast off the loop previously held on the shank of the needle. This operation is illustrated at 15^b. This movement occurs during the time that the vertical needles are at the lower part of their stroke.

Fig. 8 illustrates substantially the positions in which the ribbing needles are moved successively as the cam 20 rotates, the cam path being indicated in dotted lines in said figure and the direction of rotation of the cam being indicated by the arrow. It will be seen that the needles are projected at the lower side of the figure. The thread is picked up by the horizontal needles after they have been moved out of their farthest position and while they are moving backward again. 15^a designates the needle in which the thread is being placed. The latch at this time is open and as the needle is drawn into its slot in the dial plate the loop held on the shank of the needle slides forward, closing the latch, and drops off. The needles are again forced out by the rear cam, as shown at the upper part of Fig. 8, and during this movement the loops which have been held in the hooks slide back along the shanks, or speaking more correctly, the needles slide forward through the loops. This movement opens the latches. As shown in Figs. 4 and 22, the lower edge of the thread ring 12 is shaped to form a cam face and this cam face overlies the needles when they are at the outer portion of their stroke. The latches are opened while opposite the high portions P of the cam on the thread ring and the needles are later withdrawn, as shown at the left side of the dial in Fig. 8. When the needles are again forced outwardly, as shown at the lower part of Fig. 8, they slide through the loops held on them until the loops slip back of the latches. There is a tendency for the latches to snap into a closed position as the loops slide over them, but this action is prevented by the fact that the low part Q of the cam surface on the thread ring overlies the latches at this time. It is for the purpose of avoiding this action that the cam face is provided on the lower part of the thread ring. The needles are now ready to pick up the thread again to repeat the operation just described. It will be noted that in the construction shown there are twice as many vertical needles as horizontal needles so that a "2 to 1" rib is formed.

As above stated, the cam 20 not only gives the ribbing needles their operative move-

ment but it also controls them. That is, it retains them in their inoperative or operative positions or in the intermediate positions necessary to perform the operations of welting or tucking. The movements of the cam members 48 and 50 necessary to effect this control are transmitted through the pins 52 and 53. These pins are connected, respectively, to links 56 and 57, Fig. 9, that are pivoted to the free ends of levers 58 and 59 clamped rigidly to the top of rock shafts 60 and 61, respectively, which are mounted in the brackets 26 and 25 secured to the cam plate 7. Each rock shaft is encircled by a coiled spring which tends to turn it in the direction of the arrow associated therewith in Fig. 9. In Fig. 1 the spring so co-operating with the rock shaft 61 is indicated at 62, the lower end of the spring being inserted in a hole formed in the bracket 25 while the upper end is secured in a collar 63 clamped on the rock shaft.

Referring particularly to Fig. 9 it will be seen that the rock shaft 61 has fixed thereto an arm 64 which is provided with a curved face on its leading or forward side, and also is provided with a curved tail piece 65. The spring 62 tends to hold the parts 64, 61, 59 and 57 in the positions in which they are shown in Fig. 9, and thus to hold the pin 53 at the outer end of the slot 59 and consequently to hold the cam member 50 at the outer limit of its range of movement as shown in Fig. 14. Two latches designated at 66 and 67, respectively, Fig. 9, are both mounted on a pivot pin 68 and have hooked ends shaped to engage the tail piece 65 of the arm 64. These hooked ends lie one beyond the other and the latches 66 and 67 are acted upon by the torsion springs 70 and 71, respectively, Fig. 1, which hold their hooked ends against the tail piece 65. It is obvious that if the arm 64 were swung in a clockwise direction, Fig. 9, against the tension of the spring 62 far enough to enable the latch 66 to engage and hold the tail piece 65, the pin 53 then would be held at the inner end of the slot 55 and the cam 50 would be held in its innermost or closed position as shown in Fig. 11. Furthermore, if the latch 66 were released and the tail piece 65 were held by the hook of the latch 67, this hook being slightly farther away from the axis of the pivot pin 68 than the hook of the latch 66, the pin 53 would then be held in an intermediate or middle position, holding the cam 50 in the position in which it appears in Fig. 13.

The other cam member 48 is moved and controlled by a similar mechanism co-operating with the link 56, lever 58 and rock shaft 60. These parts, as shown in Fig. 9, comprise an arm 74 having a tail piece 75 and latches 76 and 77 turning on a pivot pin 78, all of these parts correspond-

ing to the parts 64 to 68, the only difference being that the outer ends of the parts 74, 76 and 77 lie at different levels, or elevations, from the corresponding parts at the 5 other side of the thread cylinder. This difference in elevation of these parts is utilized to effect, through an automatic mechanism, a movement of any one of the desired parts 64, 66, 67, 74, 76 or 77, as it 10 may be necessary, to effect an adjustment of one of the cam members 48 or 50.

This automatic mechanism comprises a spool shaped member 80, (hereinafter called a spool), see Figs. 2, 3 and 9, having upper and lower disk-like heads, and this spool 80 is moved into various elevations by means of connections with a cam wheel. In its different positions of elevation one or the other of its heads lie in the path of 20 rotation of the ends of one or more of the latches or arms 64, 66, 67, 74, 76 or 77, and their engagement with the spool moves them into the desired position.

In order to effect this vertical adjustment 25 of the spool 80 the spool is fixed on the upper end of a rod 81, Fig. 3, which projects through the frame of the machine and is encircled by a spring 82 bearing against a collar 83 clamped on the rod 81; this 30 spring thus tends to hold the spool 80 in its depressed position. To elevate the spool a plate 84 has its vertical end forked to straddle the rod 81 just below the spool and this plate is clamped to the upper end of 35 a vertical rod 85 which normally is held in its depressed position by a spring 86 encircling the rod and bearing against a collar 87 clamped thereto. The rod is guided in suitable brackets fixed to the machine and 40 carries a head 88 at its lower end into which is threaded a bolt 90. This bolt bears on an arm 91, Fig. 3, which is pivoted on the machine frame at 92 and has a V-shaped cam member 93 secured to its lower side in 45 position to be engaged by any one of numerous lugs 94 adjustably secured to the side of a cam wheel 95. This cam wheel 95 has a toothed periphery and it is advanced automatically by a pawl 96, Fig. 20, fast on 50 an eccentric strap 97, Figs. 1 and 20, which runs on an eccentric 98 that rotates with the main shaft 10. A spring 99 holds the pawl in engagement with the periphery of the wheel 95.

55 It will now be evident that when the machine is in operation and the main shaft 10 is rotating, the pawl 96 will effect a step by step rotation of the cam wheel 95 and that the lugs 94 on this wheel as they come 60 in contact with the V-shaped part 93 on the arm 91 will raise this arm. This motion will be transmitted through the parts 90, 88, 85 and 84 to the spool 80, raising the spool to a height depending upon the adjustment of the lug 94 with which the part

93 is in engagement. Furthermore, the length of time that the spool is held in its elevated position will depend upon the length of the lug 94.

While this cam wheel thus controls the 70 operation of the cam 20 which governs the ribbing needles, the cam wheel itself is under the control of the pattern chain 100. This chain is a part of the commercial Hemphill machine and it controls the sequence of the 75 knitting operations, the links of the chain for this purpose being provided with lugs which operate through mechanism with which the machine is equipped to produce automatically the narrowing operations at 80 the heel and toe and the other changes in the functions of the machine necessary to enable it to perform its cycle of operations. These lugs are on the right hand side of the links of the chain 100, as it appears in 85 Fig. 18. In the present machine links are used having additional lugs, one of which is indicated at 101, Fig. 18, on the left hand side of the chain. As shown in Figs. 16 and 20, the cam wheel 95 is provided on 90 its periphery with several smooth places 102. Consequently, when the pawl 96 arrives at one of these smooth places it cannot advance the cam wheel since the end of the pawl simply slides back and forth 95 in the space 102. The automatic feed of the cam wheel thus is interrupted and the links of the chain 100 carrying the lugs 101 are utilized to move the cam wheel 95 forward one tooth to place the cam wheel 100 again in the range of operation of the pawl 96.

The chain 100 rides on a sprocket wheel 103 which is rotated step by step by a pawl and ratchet mechanism, as in the commercial Hemphill machine, and the lug 101 is arranged to strike another lug 104 projecting from one side of an arm 105, Figs. 18 and 21, pivoted on the machine frame at 106 and projecting in a direction approximately parallel to the main shaft 10. This arm has an inturned end 107 that lies parallel with and close to the face of the cam wheel 95. On the cam wheel substantially in a radial line with each of the 115 smooth places 102 is a pin 108 that extends through the wheel and has an enlarged head 109 normally held against one face of the wheel by means of a spring 110. A stationary plate 112, Fig. 2, having an inclined 120 cam face is secured to the machine frame in such a position that when the pawl 96 is working in one of the smooth places 102 the pin 108 will have ridden up on the inclined face of the plate 102 and consequently will have been forced outwardly so that the enlarged head 109 will be projected away from the face of the cam wheel and will lie immediately above the inturned 125 end 107 of the lever 105.

The parts will remain in this position until one of the lugs 101 on the chain 100 strikes the lug 104 on the arm 105 and raises this arm, whereupon its end 107 will strike the head 109 of the pin 108 and move it forward carrying the cam wheel 95 with it. This movement advances the wheel 95 one tooth and enables the pawl 96 to engage in the notch next behind the smooth plate 102 and advances the wheel step by step until its operation on the cam plate is again arrested by its engagement with the next smooth place 102.

As is well understood by those skilled in this art, the pattern mechanism of the machine is designed to cause the machine automatically to knit a toe, foot, heel and leg of a stocking during each cycle, referring to the cycle as including the sequence of operations necessary to enable the machine to knit a complete stocking. The machine repeats this cycle automatically and the cam plate 95 makes one complete revolution during each cycle of operations of the machine.

The operation of the machine is as follows: The knitting operation is started in the same way that it is in the Hemphill machine and the pattern chain 100 is provided with links properly spaced to cause the machine to knit a toe, foot, and heel automatically and so much of the leg as it is desired to knit plain. During this operation, the cam 20 holds the horizontal or ribbing needles in their inoperative positions. That is, both of the cam members 48 and 50 are held in their innermost or closed positions by the latches 67 and 77. When the lug A, Fig. 16, strikes the cam piece 93 on the arm 91 it operates through the connections previously described to raise the spool 80 into the dotted line position in which it is shown in Fig. 10 at A. For convenience the cam 48 will be referred to as the rear cam and the cam 50 as the front cam. Upon the next rotation of the cam plate 7 the lower disk of the spool 80 strikes the front end of the latch 77 and trips it, whereupon the tail piece 75 immediately is moved slightly by the spring that encircles the rock shaft 60, but this tail piece is caught and held again by the latch 76. The intermediate movement, however, operates through the arm 58 and link 56 to move the rear cam into its intermediate position. This causes the ribbing needles 15 to move outwardly along the part of the dial opposite, at any instant, to the thread guide 27 and carries the latches of these needles under a stiff brush 114, Fig. 9, which is fastened to the arm 115 on which the threading ring 12 is supported. As the cam plate 7 rotates and the brush 114 comes in contact with the latches of the horizontal needles it opens them in readiness for the next operation.

The cam piece 93 next moves up on to

the small notch b' on the lug B, Fig. 16, which raises the spool 80 to the full line position, Fig. 10 at B. The latch 67 strikes the lower disk of the spool and releases the tail piece 65 which is immediately caught again by the latch 66, but the movement of the arm 64 so produced moves the front cam to its intermediate position. Both the front and rear cams are now in their intermediate positions. Consequently, the work is now caught on the horizontal needles. The cam part 93 next rises to the top of the lug B which raises the spool 80 to its uppermost position, shown in Fig. 10 at B. The upper disk of the spool 80 is struck by the arm 64 which pushes the front cam back to its closed or innermost position where it is held by the latch 66. The machine makes two rounds or courses while the needles remain in this position without casting off, thus producing a welt which serves to close up the holes that otherwise would be formed by changing from the plain knitting to ribbing.

The cam part 93 next drops on to the top of the lug C, Fig. 16, thus dropping the spool 80 into its middle or intermediate position, shown in Fig. 10 at B. In this position the lower disk on the spool strikes both the latches 66 and 67 thus completely releasing the front cam and enabling the spring 62 to move this cam to its forward position. The rear cam still remains in its intermediate position; in other words, the cams are in the position shown in Fig. 14. In this position the machine performs the ribbing operation as previously described, the needles being advanced by their engagement with the high part of the front cam and retracted after this high part has passed and the thread has been picked up by the needles.

The operations so far described illustrate the manner in which the cam lugs on the cam plate 95 effect the adjustment of the front and rear cam members 50 and 48 of the cam 20. Any further detailed description of the operation produced by the different cam lugs, therefore, is believed to be unnecessary. It may be stated, however, that the particular arrangement of lugs shown in Fig. 16 is such that the lug D adjusts the cam 20 to make a welt near the top of the ribbed cuff, the lug E causes the machine to continue the ribbing operation again and these operations are repeated by the lugs F and G, H and I, and J, K and L. That is, four rows of welting are made in the stocking, each of the lugs D, F and H, being long enough to cause the machine to make a welt of two courses, while K causes the machine to make a welt of four courses. The lug M produces a tuck course or courses and the lugs N and O let the work off the ribbing needles and cause the machine to resume the plain knitting operation.

It may also be stated that in letting the

work off the ribbing needles it is merely necessary to move the front cam to its middle position and then close it completely and open the rear cam to its farthest position, 5 thus forcing the ribbing needles out to the extreme limit of their movement and sliding the loops that they hold back over the latches of the needles. When the needles are pulled inwardly again during their travel through 10 the path in the rear cam, the loops slide off over the latches. This casts the work off the ribbing needles and the rear cam is then closed to move the needles into their inoperative positions. These movements are produced automatically by the movement of the 15 spool 80 through certain of the positions illustrated in Figs. 10 at C and D as will readily be understood without detailed description.

In this connection it will be understood 20 that a welt is produced when the work is held on the ribbing or horizontal needles, but these needles are not advanced far enough to pick up the thread. Similarly, a tuck is produced when the adjustable cams are in their intermediate 25 positions so that they advance the needles far enough to pick up the thread but do not allow the needles to advance far enough to cast off the work.

Attention is particularly called to the very 30 simple construction of the cam 20 that controls the ribbing needles. It will be seen that this cam has only two moving parts and that each of these parts is adjustable on a pivot. Furthermore, this cam is so constructed 35 that it is a very simple matter to remove a ribbing needle from the dial whenever a needle becomes broken or otherwise injured. It is merely necessary to turn the cam until one of the spaces between the members 40 45 and 50 or between the parts 44 and 48 is opposite the groove in which the broken needle is located. The needle may then be drawn out of the dial plate and replaced by a new one. This cam can rotate in either direction to give the horizontal needles a knitting movement. Each of the needle grooves, or races, terminates at the outer edge of the dial plate in an inclined notch, as indicated in Fig. 8, and the needles draw the work into 50 these notches when the needles are moved backward during the knitting operation to cast off the loops, the inclined notches facilitating the casting off of the loops.

The machine is equipped with the usual 55 web takeup mounted near the lower end of the web guide 4, this takeup not being shown in the drawings. An auxiliary takeup is also located in the web guide for the purpose of maintaining a tension on the goods at the 60 point where the heel or toe is formed. The takeup with which the Hemphill machine ordinarily is equipped does not apply sufficient tension to the stocking to pull out the pocket that is formed at the heel and toe and 65 this auxiliary takeup is designed to act upon

this particular part of the stocking at a point relatively close to the needles and thus avoid any flaws in the goods that might be produced due to the looseness or slack material formed at the heel and toe.

70

This additional takeup mechanism comprises a pinion 116, Figs. 1 and 3, mounted fast on the main shaft 10 and driving a train of gears 117, 118 and 119. The last of these gears, 119, see particularly Fig. 23, 75 is mounted loosely on a stub shaft 120 on which also is loosely mounted a ratchet wheel 121 and a bevel gear 122. A pawl 123 carried by the gear 119 engages the teeth of the ratchet wheel 121 and drives 80 this wheel and the bevel gear 122 when the machine is driven in its normal direction of rotation. It does not, however, drive the ratchet wheel when the machine is reversed. The bevel gear 122 meshes 85 with another bevel gear 124 rotating freely on a shaft 125 which is connected by a bracket 126 with the shaft 120. A sleeve 127 and a pulley 128 both rotate with the gear wheel 124. A bracket arm 129 is secured to the inner end of the shaft 125 and projects upwardly within the web guide 4, as shown in Figs. 1, 2 and 3, and this bracket arm supports a pulley 130 at its upper end. A belt 131 is mounted on the 90 pulleys 130 and 128 and is driven by the connections with the pinion 116. This belt preferably is made of rubber, fabric, or some material designed to exert a friction or dragging action upon the web of knitted 95 fabric that hangs downwardly within the web guide 4. A spring 132, Fig. 2, acts on the bracket arm 129 to press the pulley 130 lightly against the shank of the dial plate 16. The belt 131 at the point where it 100 passes over the pulley 130 thus presses the material in the heel and toe parts of the stocking against the lower part of the member 16 and stretches it, pulling out the looseness that otherwise would be present, and thus applies the tension to the goods that 105 is necessary to enable the ribbing needles to properly function in case they are brought into operation immediately after the foot of the stocking has been formed.

110

While I have herein shown and described the best embodiment of the invention of which I am at present aware, it will be understood that this embodiment may be modified in various particulars without departing from the spirit or scope of this invention.

115

What is claimed as new, is:

A knitting machine having, in combination, a circular set of vertical needles for knitting a plain tubular fabric, a horizontal set of needles arranged to cooperate with said vertical set to knit a ribbed fabric, a stationary dial supporting said horizontal needles within said vertical set of needles,

120

125

130

a rotatable cam acting on said horizontal needles to give them a knitting movement, said cam being adjustable to vary the operation of said horizontal needles, means comprising a plurality of latches located at different elevations and rotating with said cam for holding the cam in different positions of adjustment, a relatively stationary device adjustable into different elevations to engage and operate said latches, a cam wheel having lugs thereon, connections whereby said lugs are operative to adjust said stationary device, said cam wheel having a toothed periphery with teeth omitted therefrom at intervals, a driven pawl for engaging the teeth of said cam wheel to rotate it step by step, said pawl being inoperative, however, to rotate said cam wheel when it engages the points on said wheel at which a tooth is omitted, a pattern chain automatically controlling the sequence of the knitting operations of the machine, a plurality of spring pressed pins carried by said cam wheel, cam means for projecting one of said pins whenever the wheel is moved into a position such that its feeding movement by the pawl is interrupted, and means arranged to be operated by lugs on said pattern chain and operative to engage a pin so projected and thereby to move the pin so engaged and said cam wheel far enough to cause said pawl again to operatively engage the teeth of said cam wheel.

In testimony whereof I have signed my name to this specification.

GILBERT MURPHY.
